Int. Cl. D15—06

U.S. Cl. D49—1

Fig. 4

Fig. 5

FIG. 1 is a front elevational view of a combined washer-dryer laundry appliance embodying my new design;

FIG. 2 is a side elevational view of the right side as taken along the line 2—2 of FIG. 1;

FIG. 3 is a top plan view as taken along line 3—3 of FIG. 1;

FIG. 4 is a rear elevational view as taken along line 4—4 of FIG. 2; and

FIG. 5 is a left front perspective view thereof.

It is to be understood that the left side thereof is similar but opposite to FIG. 2.

I claim:

The ornamental design for a housing for a combination washer-dryer laundry appliance, as shown and described.
